To all whom it may concern:

Be it known that I, Leroy L. Salfisberg, a citizen of the United States, and a resident of South Orange, in the county of Essex and State of New Jersey, have invented a new, original, and ornamental Design for a Package Envelope or Similar Article, of which the following is a specification, reference being had to the accompanying drawing forming part thereof.

Figure 1 is a plan view of a package envelope showing my new design.

Figure 2 is an edge elevational view of the package envelope.

Figure 3 is a fragmentary transverse sectional view on the line 3—3 of Figure 1.

Figure 4 is a fragmentary plan view on an en-

larged scale of a portion of the package envelope or similar article and

Figure 5 is a fragmentary top plan view of the portion of the package envelope or similar article shown in Figure 4.

The characteristic features of my design reside in the portions shown in full lines and the design is characterized by the elongate oval shaped transparent portion arranged within a generally rectangular translucent diagonally crimped border and symmetrically embossed on both of opposite sides, as shown.

I claim:

The ornamental design for a package envelope or similar article, as shown and described.
